(57) **CLAIM**

(21) Appl. No.: **29/210,214**

We claim the ornamental design for air conditioner integrated with picture design, as shown and described.

(22) Filed: **Jul. 29, 2004**

DESCRIPTION

(30) **Foreign Application Priority Data**

Jan. 31, 2004 (KR) 30-2004-0002394

FIG. 1 is a perspective view of air conditioner integrated with picture design showing our new design:

(51) **LOC (8) CI.** **23-03**

FIG. 2 is a front view thereof;

(52) **U.S. CI.** **D23/354**

FIG. 3 is a rear view thereof;

(58) **Field of Classification Search** D23/351-354;

FIG. 4 is a left-side view thereof;

312/236; 62/259.1, 304, 259.4, 262-263;

FIG. 5 is a right-side view thereof;

454/330-331; D14/485, 489, 494

FIG. 6 is a top plan view thereof;

See application file for complete search history.

FIG. 7 is a bottom plan view thereof; and,

(56) **References Cited**

FIG. 8 is an enlarged fragmentary front view thereof, with portions omitted for clarity of illustration.

U.S. PATENT DOCUMENTS

The broken line disclosure in the views forms no part of the claimed design.
